Specification for Design.

Patented June 20, 1911.

Application filed April 14, 1910. Serial No. 555,548. Term of patent 7 years.

To all whom it may concern:

Be it known that we, HERMAN C. STROBEL and LORENZ KILLIAN, citizens of the United States, residing at New York, in the county of New York and State of New York, and Brooklyn, county of Kings, and State of New York, have invented a new, original, and ornamental Design for Tables, of which the following is a specification, reference being had to the accompanying drawing, forming a part thereof.

The invention consists in a hexagonal spindle or column supporting a plain round table top with a tripodal base connected with the base of the spindle and raised above the

floor, the legs of such tripod extending in curves outwardly and downwardly and terminating in feet which rest upon the floor with conventional leaves carved or otherwise produced in raised effect upon the legs adjacent and joining with the base, and a mold joining the base with the spindle.

We claim—

The ornamental design for a table as shown and described.

HERMAN C. STROBEL.
LORENZ KILLIAN.
